UNITED STATES PATENT OFFICE.

JOHN B. MULHOLLAND AND ALFRED F. BORSCHEL, OF BUFFALO, NEW YORK.

SAFETY TARGET ATTACHMENT FOR AIR RIFLES.

Application filed March 29, 1922. Serial No. 547,663.

Our invention relates to improvements in safety target attachments for air rifles.

Air rifles are invariably of simple construction, light in weight, and cheap, and although not possessing the force or carrying capacity of a regular rifle having shot projected therefrom by the force of explosion, the price at which they can be purchased has made them very popular with 10 boys; but due to the carelessness with which air rifles have heretofore been handled by boys, resulting in many accidents, the sale of them has been forbidden in many places by law or city ordinances, with the result that the pleasure of possessing an air rifle and the prospects of acquiring marksmanship, have been denied boys of the present generation in many sections of the country.

It is the purpose of our invention to provide an attachment for an air rifle, which will enable boys to own one and at the same time assure safety against accidents, and as the attachment is one furnishing a target to shoot at, the same pleasure and the ability to acquire marksmanship will be open to boys by the use of this invention that they have possessed prior to the enactment of the forbidding laws or ordinances above referred to.

A further object of our invention is the provision of an attachment which may be made in various lengths, and which is so mounted on the barrel of the rifle that skill must be displayed in order to secure results in practice.

A still further object of our invention is the provision of a safety device for rifles, which may be permanently secured to air rifles at the plants of production or, if desired, may be detachably fitted to the rifles at such places, or to air rifles now in possession of boys and the use of which is forbidden in their present condition.

A still further object of our invention is the production of a simple and inexpensive device of the kind described, which may be of any length, preferably from eight inches up, and to provide a tripod or other suitable support for the outer end of the device if of a length greater than can be conveniently supported from its point of attachment to the barrel of the rifle.

The invention consists in providing a target device at the outer end of the barrel 55 of an air rifle.

It also consists in providing an elongated guard between the end of the rifle barrel and the target.

It further consists in providing a device of this kind having a target equipped with 60 duplicate parts and means to sight to one of said parts and to direct the shot from the air rifle against or through the other part at the point corresponding to that sighted on the first-mentioned part.

It further consists in the novel features of construction, and in the arrangement and combination of parts to be hereinafter described and more particularly pointed out in the subjoined claims.

In the drawings:—

Fig. 1 is a side elevation of a repeating air rifle equipped with our invention.

Fig. 2 is a transverse section taken on line 2—2, Fig. 4, looking in the direction of the 75 arrow crossing said line.

Fig. 3 is a transverse section taken on line 3—3, Fig. 4, looking to the right.

Fig. 4 is a central vertical section through our improved target device or attachment 80 and the adjacent end of the barrel of the rifle to which it is attached.

Fig. 5 is a transverse section taken on line 5—5, Fig. 4, looking in the direction of the arrow crossing said line.

Fig. 6 is a longitudinal section taken through the securing sleeve or connector whereby our improved device is fastened to the outer end of the barrel of a rifle.

Fig. 7 is a plan view of our duplicate 90 target.

Our invention, while particularly adapted for air rifles, may with slight modifications be used in connection with any kind of firearm, but it will be apparent from the description to follow that, when applied to other than air rifles, the device will be enlarged; at least extended in the direction of its length.

In the drawings we have shown the device 100 in connection with a repeating air rifle having a magazine, adapted to be filled with shot, inserted into the barrel of the rifle. When attached to a rifle of this kind, the device is preferably detachably secured in 105 order to enable the magazine to be withdrawn from the barrel of the rifle when emptied so that another, supplied with shot, may replace it or so that it may be refilled and conveniently re-inserted into the rifle.

When, however, the device is applied to a single shot rifle, it may be permanently, or removably applied, as may be desired.

The rifle to which the device is shown applied in the drawings is of the type known as a repeating air rifle having the usual trigger mechanism between the stock 8 and the barrel 9 of the rifle, said trigger mechanism co-acting with proper projecting mechanism to project a shot from the rifle, but since these parts are well understood and form no part of our invention, they are not illustrated, except such parts thereof as may be exposed.

15 Inserted into the barrel of the rifle is a shot magazine 10 having two longitudinal bores 11, 12, the first of which is the shot-retaining bore and the second the shot-directing bore, the projecting mechanism within the rifle being constructed or associated with means for drawing one shot after another from the shot-retaining bore into the shot-directing bore. The shot-directing bore is positioned axially within the barrel of 25 the gun, and at the outer end of this magazine a flange or projecting portion 13 is provided, which bears against the end of the barrel 9.

14 designates an attaching element or connector in the form of a cylinder or sleeve, closed at its outer end and having an opening 15 in said end at least as large in diameter as the shot-directing bore 12 with which it is aligned. This sleeve is detachably secured to the end of the barrel 9, and for this purpose said barrel has projecting pins 16 at diametrically opposite points, preferably at opposite sides, while the sleeve has longitudinal slots 17 extending inwardly from its inner edge which terminate in offset or angular portions 18. These slots and pins form what is known as a bayonet joint and serve to permit of conveniently attaching the sleeve to the barrel, and also as readily removing the same therefrom. When applying a sleeve of this kind to an old rifle provided with a sight projection at or near the outer end of the barrel, such as shown at 19, the sleeve is provided interiorly with an elongated groove 20 extending from the inner end of the sleeve forwardly and terminating in a right angular portion 21; thus when a sleeve of this kind is employed for attachment to an air rifle having a sight projection, such as 19, the groove 20 enables the sleeve to be secured to the barrel of the rifle by alining said groove with said sight projection, and thrusting the sleeve onto the barrel, which will cause the sight projection to strike the inner or forward end of said groove, and by turning the sleeve of the barrel slightly, the sight projection will enter the right angular portion 21 of said groove. While this action takes place, the pins 16 will become alined

with the slots 17 and enter the same during the placing of the sleeve onto the barrel, and when turning the sleeve as described, said pins will enter the offset or angular portion 18 at the inner or forward ends of 70 said slots and thus lock the sleeve to the rifle barrel.

Between the outer end wall of said sleeve and the flange 13 of said shot magazine, a flat split spring 22 is interposed, the function of which is to force the sleeve outwardly and retain the pins 16 in the offset angular portions of the slots 17. In this manner, assurance is had that the sleeve will be held against accidental detachment from the barrel, although readily removable by exerting pressure inwardly on the sleeve, then rotating the sleeve slightly and pulling the same outwardly or forwardly.

When our improved device is detachably secured to an air rifle at the place of production and the rifle is made expressly to accommodate our attachment, the sight projection 19 may be dispensed with, thus making it unnecessary to provide the groove 20 with its angular portion, in the sleeve.

We preferably provide the sleeve with a sight projection 23, which may have a sight opening 24 therethrough, but any other form of sight may be substituted for that shown.

While the sleeve 14 serves as part of our improved device, it is, in its more limited sense, a means for securing the device to the barrel of the gun.

Surrounding the sleeve 14 is a swivel annulus 25 through which, at diametrically opposite points, securing screws 26 are passed. These screws have pointed inner ends adapted to engage the sleeve 14, and slight depressions are preferably formed in the sleeve at 105 diametrically opposite points to receive the pointed ends of said screws. The annulus 25 has an internal diameter somewhat larger than the external diameter of the sleeve which it surrounds, and therefore an annular space is provided between the two which enables said annulus to be swung horizontally on the screws 26, or pivots, as they may be termed.

27 designates a cage or guard pivotally secured at its inner or rear end to the annulus 25 and having a suitable target, to be hereinafter described, at its front end. This cage comprises an elongated casting or stamping 28, which is parti-circular in 120 cross section, and a series of parallel wires 29 arranged and secured, as will be presently described.

The rear end of the parti-circular casting or stamping straddles the swivel annulus 25 and has screw pivots 30 passed therethrough which engage said annulus at diametrically opposite points, preferably at right angles to the screw pivots 26, and secure said annulus to the sleeve 14, thus providing for 130

slight vertical movement of the cage. To permit of this, the straddling parti-circular portion of the cage is separated from the exterior of the swivel annulus 25 by an intervening space. The exterior of the swivel annulus is preferably provided at diametrically opposite points with slight depressions to receive the pointed ends of the screw-pivots 30. By the use of the screw-pivots 30, swivel annulus 25; and screw-pivots 26, a universal connection is provided between the cage and the sleeve 14.

It is apparent that when applying our improved safety target device, as it may be termed, to certain types of air rifles or to firearms, the sleeve 14 may be dispensed with and the swivel annulus 25 be pivotally secured to the barrel of the gun.

The cage 27 has a box-like structure 31 formed on or secured to the outer or front end of the parti-circular casting or stamping 28, which casting or stamping may, in its broader sense, be referred to as a frame. Connecting opposite edges of the frame in proximity to the outer end of the sleeve 14 is a band 32, to which the rear ends of the guard wires 29 are secured, the forward ends of said wires being secured to the box-like structure 31. These wires which are spaced in close relation and are preferably parallel, serve with the parti-circular frame 28 to form a complete enclosure or enclosed passage through which the shot from the air rifles are projected. It is of course understood that the upper portion of the frame may be enclosed by means other than the parallel wires referred to, and while we consider it an advantage to have the upper portion of the cage formed of open-work material or provided with spaces to enable the interior of the cage to be seen, this is not absolutely necessary. We, however, have found that by employing slender wires to close the upper portion of the cage, a lighter construction is provided and an effective guard furnished.

The box-like structure 31 is preferably cylindrical transversely but may be otherwise shaped, and its rear wall 33 has an opening 34 therein, which may be of any desired size. The cylindrical wall 35 of said box-like structure has a slot 36 in line with the front surface of the rear wall of said structure through which a target 37 is inserted. Said target is elongated, as shown in Fig. 7, and approximately one-half thereof extends outwardly above the box-like structure, or what may be termed target casing, while the other half extends into said casing, each half having a picture, symmetrical figure, or any other matter printed, embossed or otherwise applied thereto which will serve as a target and which may have a determining point or spot, or vital region to be shot at; the picture, symmetrical fig-

ure, or other matter printed or otherwise applied to the lower half of the target being exposed through the opening 34 in the rear wall of the target casing so that a shot projected from the rifle will carry through 76 the cage or guard 28 and pass through said opening 34 so as to strike or penetrate the target, depending on the material of which the target is made.

It is to be noted that adjacent the region 75 of the trigger mechanism of the rifle the usual sight 38 is provided, and in aiming at the target, this sight is used in connection with the sight 33 on the sleeve 14 applied to the outer end of the rifle barrel, these two 80 sights being used to sight a point on the upper exposed half of the target 37. When these two sights are in direct alinement with a certain point on said upper half of the target, the shot projected from the rifle will 85 strike or penetrate, as the case may be, the corresponding point on the lower half.

Forward of the target 37, the bottom of the target casing is provided with a forwardly inclined portion 39, which leads to 90 an opening 40 in said bottom, so that when paper, cardboard, or any other material capable of being penetrated by a shot is used as the target, the shot will pass through the target and strike the front wall of the target 95 casing. The shot after having lost its force by contact with said wall, will gravitate through the opening 40 or strike the inclined portion of the bottom of said casing and roll out through said opening. 100

We have provided a bell or other audible signal 41 on the front wall of the target casing, and this signal may be sufficiently small so that it will be necessary to penetrate the target at the vital or determining 105 point, or in close proximity thereto, in order to give the signal. Should the shot strike the target and penetrate at the outer regions of the same, the shot would pass the signal and strike the front wall of the 110 target casing, which would merely create a dull sound capable of being readily distinguished from the ringing sound of the bell.

The target 37 can be constructed of cheap 115 material and both sides thereof used. On one of them may be printed, for instance a picture of a man, and the vital spot thereon could be the head or a point indicating the location of the heart, either 120 one might be away from the exact center of the target or, more particularly, either half of the target. A second may have the picture of an animal whose head may be at a low point of the target and indicate the vital point of this picture to be shot at. A third may have a circular spot surrounded by concentric gradually enlarged circles and the circular spot may be disposed at the exact center of the target. This 130

change in position may be carried out indefinitely, and for this reason the flexible connection of the target device to the barrel of the air rifle is a vital feature of our invention. As a means to provide this flexibility, we have adopted the universal connection hereinbefore referred to, which will enable the user of the rifle to position the target with respect to the sights 23 and 38 so that the exercise of skill is necessary to determine marksmanship, and while the target is positioned with respect to the sights, rather than the rifle being positioned with respect to the target, the results to determine marksmanship are substantially the same in both cases. Where our improved target device is made of considerable length, skill will be the vital factor in determining marksmanship.

For the purpose of manipulating our improved target device to position the target with respect to the sights 23 and 38, we provide a handle 42 which is fastened to the frame 28 of the cage and extends rearwardly, the rear end thereof being provided with a loop 43 so that a finger can be conveniently placed through it and the device swung upwardly or downwardly, or laterally in either direction, or at any angle desired to position the target with respect to the sights 23 and 38. Pictures or other objects may be printed on both sides of the target so that when one side is shot at, the target may be reversed, and when made of paper or other inexpensive material, the cost of owning and operating an air rifle equipped with our invention will be comparatively small.

An air rifle equipped as described will safeguard the public against injury, while providing an interesting pastime for boys which, in addition thereto, will enable them to acquire ability toward marksmanship which may be used to advantage in later years.

Where the target device is of considerable length, the outer end thereof may be supported in any suitable manner, but we preferably provide a tripod 44, the upper end of which may be detachably secured to the target casing, or otherwise. In the construction shown, an internally threaded socket 45 is provided in the bottom of the target casing and the tripod provided with a threaded reduced upper end 46, which forms a shoulder and which is threaded into said socket so that the shoulder is engaged by the under side of the bottom of the target casing. When a tripod is used, or the front end of the target device is otherwise supported, adjustment is effected by positioning the rifle with respect to the target, which more closely approaches the manner of ordinarily aiming at a target or object located at a distance and disconnected from

the rifle, this being allowed, due to the universal connection between the target device and the rifle; but if desired, said device may be manipulated by the use of the handle 42. It is, however, believed that greater pleasure and more accurate marksmanship can be acquired by merely adjusting the rifle to the target while permitting the rear end of the target device to adjust itself to the changing position of the front end of the barrel.

Having thus described our invention, what we claim is:—

1. The combination with a rifle, of a sleeve detachably secured to the outer end of the barrel of said rifle, an annulus surrounding said sleeve and pivotally secured thereto, an elongated frame pivotally secured to said annulus and having its pivots at right angles to the pivots of said annulus, and means for supporting a target at the outer end of said frame.

2. The combination with a rifle, of a sleeve secured to the outer end of the barrel of said rifle by means of a bayonet joint, an annulus surrounding said sleeve and having an internal diameter somewhat greater than the external diameter of said sleeve and being swiveled thereon, an elongated target support swiveled to said annulus at an angle to the swiveled connection of said annulus to said sleeve, a target at the outer end of said target support, and means for stopping the shot after penetrating said target.

3. The combination with a repeating rifle having a shot magazine therein, of a sleeve detachably secured to the outer end of the barrel of said rifle and having its outer end closed and provided with a small axial opening, a target device universally connected to said sleeve and having a target casing at its front end, and a target removably entered in said casing.

4. The combination with an air rifle having the usual sights at the front and rear of the barrel thereof, of a sleeve provided with an internal longitudinal groove extending forwardly from its rear end and terminating at its front end in an angular portion adapted to receive the sight at the front end of the rifle barrel, and a target device flexibly connected to said sleeve.

5. The combination of a rifle having a shot magazine therein provided with a flange at its outer end adapted to bear against the outer end of the barrel of said rifle, a sleeve secured to the outer end of said barrel by a universal joint and having its outer end closed and provided with an opening alined with the shot-directing bore of said magazine, a spring interposed between the outer end of said sleeve and the flange of said magazine, and a target device connected to said sleeve.

6. The combination with an air rifle having a sight at the inner end of its barrel, of a sleeve detachably secured to the outer end of said barrel and having a sight projecting therefrom adapted for cooperation with said first-mentioned sight, a target device having a target support and being universally connected to said sleeve, and a target having duplicate target parts, one of which is to be sighted at through the medium of the sights on said barrel and sleeve and the other to be shot at.
7. A target device to be attached to the front end of the barrel of a rifle comprising an elongated frame of parti-circular formation in cross section and having a band connecting opposite edges of said parti-circular portion near the point of connection of said frame to said rifle, said frame having a box-like structure at its front end, wires connecting the rear wall of said box-like structure with said band, and a target having a shooting portion in said box-like structure and a sighting portion extending from said box-like structure.
- 25 8. The combination with a rifle, of a tar-

get device swiveled to the front end of the barrel of said rifle and having a box-like structure at its front end provided with an opening in its rear wall, a slot in its upper wall and an inclined thickened portion on its bottom, said bottom having an opening in advance of said inclined thickened portion, a signal in a position in advance of the opening in said rear wall, and a target inserted through the slot in the upper wall of said box-like structure and having a portion to be shot at exposed through the opening in said rear wall and a portion extending outwardly from said box-like structure to be sighted at.

9. The combination with a rifle, of a target device universally connected to said rifle and having a target at its front end and a handle extending rearwardly from its rear end to permit of adjusting said target device for the purpose of sighting the desired point on the target.

In testimony whereof we affix our signatures.

JOHN B. MULHOLLAND.
